United States Patent Office.

ANDREW ROBES, OF SOMERVILLE, AND JOHN C. CHAPMAN, OF CAMBRIDGEPORT, MASSACHUSETTS.

Letters Patent No. 94,241, dated August 31, 1869.

IMPROVEMENT IN PIPE-WRENCH AND PIPE-CUTTER.

The Schedule referred to in these Letters Patent and making part of the same.

To all whom it may concern:

Be it known that we, ANDREW ROBES, of Somerville, and JOHN C. CHAPMAN, of Cambridgeport, in the county of Middlesex, and in the State of Massachusetts, have invented certain new and useful Improvements in Gas-Fitters' Tools; and do hereby declare that the following is a full, clear, and exact description thereof, reference being had to the accompanying drawing, making a part of this specification, in which—

Figure 1 is a side view of our improved device;

Figure 2 is a front view of the same; and

Figure 3 is a longitudinal cross-section, on the line $x x$ of fig. 1.

Letters of like name and kind refer to like parts in each of the figures.

Our invention is an improvement in gas-fitters' tools; and

It consists in the peculiar construction and arrangement of the several parts, by means of which a combined device is produced that, while capable of performing in a superior manner the office of pipe-wrench, is more especially adapted for use in cutting gas-pipe.

In the annexed drawing—

A represents the body or frame, consisting of a long and short vertical side piece, a and a' , joined together at their lower ends, the former of which is bent over at its upper end, so as to form the upper or fixed jaw a' .

Sliding between the side pieces, is a block, b , which is held therein by flanges b' , projecting outward from either side thereof, and is adjusted vertically by means of a screw, d , which passes upward through a suitable opening in the bottom of the frame, and is swivelled at its upper end within the lower end of said block.

The opening in the frame through which the screw passes, being provided with a female thread, corresponding with the male thread upon said screw, by turning the latter to the right or left, the block or lower jaw b will be correspondingly adjusted to or from the upper jaw, so as to firmly clamp or release anything placed between.

A handle, h , is attached to the screw below the frame, and furnishes a means by which said screw may be adjusted, after which it can be secured in place by means of a jam-nut, m , immediately beneath said frame.

When thus constructed, it will be readily seen that this device can be quickly adjusted upon, and made to firmly clasp pipe of any suitable size, and that, from the strength and simplicity of its parts, great durability and convenience will result.

Passing upward, through a suitable opening in the centre, lengthwise of the screw and the adjustable jaw, is a rod, C , having upon its upper end a cutter, c , of suitable shape.

The opening through the jaw b corresponds in size and shape with the body of the cutter, which, being placed with its cutting point to the front, is thereby retained in its proper position.

g represents a sleeve or long nut, fitting over or upon the screw d , and having attached to its lower end, and forming a part thereof, a cross-bar, k , by means of which it is operated or revolved upon said screw.

The lower end of the rod c is swivelled within the sleeve by means of a collar, held in place vertically within said sleeve by a nut, n , and a plug, l , as shown in fig. 3.

This arrangement permits the adjustment of the cutter c above the upper surface of the movable jaw b , as by revolving the sleeve g , it is raised or lowered upon the screw d , and produces a corresponding motion of the rod and cutter.

The device is now complete, and is operated for pipe-cutting as follows:

The cutter being withdrawn below the upper surface of the jaw b , the pipe is placed within, and the jaws adjusted together until said pipe will turn freely between them, without lateral motion, when they are secured in place by means of the jam-nut m . The pipe, being now caused to revolve, and the cutter adjusted until it touches the surface, a groove is cut therein, which is increased in depth at each revolution by slightly raising said cutter until said pipe is neatly divided.

The advantages possessed by this device are as follows:

First, it furnishes, in a compact form, a combined tool, capable of performing in a superior manner the office of two heretofore separate devices, whereby greater convenience is secured, and the cost materially lessened.

Second, the peculiar construction and arrangement of the several parts, renders the tool the most effective of any ever constructed for the purpose of cutting pipe, it being necessary to give the pipe or cutter but six revolutions in order to complete the operation.

In addition to the foregoing, said tool can either be secured in a vise, and the pipe caused to revolve, or the pipe can be made stationary, and the tool revolved around it, as may be desired.

Third, from the form and simplicity of the various parts, there is little liability of their getting out of order, and great durability is insured to the device.

Having thus fully set forth the nature and merits of our invention,

What we claim as new, and desire to secure by Letters Patent, is—

The tool *k*, within the hollow screw *d* and block *b*, rendered adjustable, with reference to said screw and block, by means of the sleeve-nut *g*, nut *n*, and plug *l*, substantially as shown and set forth.

Also, the within-described combined wrench and pipe-cutter, consisting of the frame *A*, adjustable jaw

or block *b*, hollow screw *d*, handle *h*, jam-nut *m*, rod and cutter *c*, sleeve-nut *g*, nut *n*, and plug *l*, all constructed and arranged substantially as specified.

In testimony that we claim the foregoing, we have hereunto set our hand, this 2d day of August, 1869.

ANDREW ROBES.
JOHN C. CHAPMAN.
